DESIGN FOR A METALLIZED FUNERAL WREATH

Wayne L. Mallett, Valparaiso, Ind.

Application March 7, 1939, Serial No. 83,409

Term of patent 14 years

To all whom it may concern:

Be it known that I, Wayne L. Mallett, a citizen of the United States, residing at Valparaiso, in the county of Porter and State of Indiana, having invented a new, original, and ornamental Design for Metallized Funeral Wreaths, of which the following is a specification, reference being had to the accompanying drawing, forming part thereof.

Fig. 1 is a front elevational view of a metallized funeral wreath showing my new design.

Fig. 2 is a section on line 2—2 of Fig. 1.

What I claim is:

The ornamental design for a metallized funeral wreath, as shown.

WAYNE L. MALLETT.
